INVENTOR

Leeds

WITNESS:

ATTORNEY

UNITED STATES PATENT OFFICE

JOHN H. BARGESSER, OF MCKEES ROCKS, PENNSYLVANIA

LUBRICATING DEVICE

Application filed February 20, 1928. Serial No. 255,746.

This invention relates to lubricating devices for use in connection with a swingingly mounted member, such as porch swings and the like, an object being to provide means for supplying lubricant at the points of engagement between the hanger hooks or eyes, and the supporting hooks of the swing chains, so as to eliminate objectionable noise and reduce friction and wear.

10 Another object of the invention is the provision of means of the above character which are simple in construction, efficient in use, and may form a permanent part of the hangers or hooks, or may be in the nature 15 of an attachment.

With the above and other objects in view, the invention further includes the following 20 novel features and details of construction, to be hereinafter more fully described, illustrated in the accompanying drawing and 25 pointed out in the appended claims.

In the drawing:—

Figure 1 is an elevation showing a swing with the invention applied.

25 Figure 2 is an enlarged sectional view taken substantially on the line 2—2 of Figure 1.

Figure 3 is a detail view of the lubricant container.

30 Figure 4 is a like view of one of the chain carried hooks.

Figure 5 is a perspective view showing a slightly different form of the invention.

Figure 6 is an elevation partly in section 35 showing a further modified form of the invention.

Figure 7 is a transverse sectional view of the same.

Referring to the drawing in detail where- 40 in like characters of reference denote corresponding parts, the invention is shown in connection with a swing 10 which is hung from a suitable support 11 through the me- 45 dium of chains 12 and hanger elements 13. These hanger elements may be in the form of either hooks or eyes which are adapted to be engaged by hooks 14 carried by the chains 12.

In order to eliminate the rubbing or 50 squeaking noises frequently experienced in

the use of swings supported in this manner, the present invention provides means for lubricating the hanger element 13 and the hook 14 at their points of engagement. In Figures 1 to 4 of the drawing, this is accom- 55 plished by providing a container 15, which is adapted to contain hard grease or other lubricant and which is engaged by the hook 14. For this purpose, the hook 14 is provided intermediate its ends with an offset 60 upwardly extending portion which includes parallel arms 16 and 17. The arm 16 is connected to the shank 17' of the hook by means of a rightangled portion 18, while the arm 17 carries a hook 19 which is adapted 65 to engage through the hanger element 13. The arms 16 and 17 have a clamping engagement with one wall of the container 15 and the latter is provided with a notch 20 at this point to receive the bight 21 which 70 connects the arms. The bottom of the container is provided with a spring arm 22 whose free end carries a hook-shaped extremity 23 which engages the rightangular portion 18 of the hook 14. This acts to 75 force the bight portion 21 into the notch 20 and to hold the container 15 in place.

In Figure 5 of the drawing, the hanger element 13' includes a cup-shaped container 24, while the hook 25 which engages this 80 hanger element is provided with opposed hook-shaped arms 26 for engagement over the edge of the lubricant container 24.

In Figures 6 and 7 there is illustrated a further modified form of the invention in 85 which the container 27 is rectangular in plan and V-shaped in transverse section. This container is provided with an opening for the passage of a hanger element 28 which is shown in the form of a lag bolt, the opening being surrounded by a boss 29. At the bottom of the opening is a recess 30 which receives the head 31 of the lag bolt. Instead of a hook, this form of the invention utilizes a looped member 32 whose opposite 95 ends are provided with inwardly extending hooks 33 which engage over the walls of the container 27 with the bills of the hooks positioned within the angle at the bottom of the container. A bearing is thus provided 100

upon which the bills of the hooks may rock.

The invention is susceptible of various changes in its form, proportions and minor details of construction and the right is herein reserved to make such changes as properly fall within the scope of the appended claims.

Having described the invention what is claimed is:—

- 10 1. A lubricating device comprising in combination with a hanger element, a supporting hook swingingly engaged therewith and a lubricant container located at the point of engagement of the hook with the hanger element.
- 15 2. A lubricating device comprising in combination a transversely V-shaped container, a hanger element extending through said container for engagement with a supporting structure, a looped member, and inwardly extending extremities provided at the opposite ends of the looped member and receivable within the angular bottom of the V-shaped container, whereby the looped member will be swingingly supported.

In testimony whereof I affix my signature.

JOHN H. BARGESSER.
